PAINT BUCKET ATTACHMENT

Robert A. Spitz, Waukegan, Ill.

Application February 15, 1939, Serial No. 256,583

1 Claim. (Cl. 91—63)

This invention relates to new and useful improvements in attachments for paint buckets and more especially to a device for holding paint brushes and which incorporates means whereby a paint brush can be wiped of surplus paint, thus eliminating the dripping of paint from overfilled brushes and further, the running of paint down the side of paint buckets when the edge of the can is relied upon as a wiper.

10 An important object of the invention is to provide a simple and inexpensive device in the form of an attachment which can be furnished with every bucket of paint and discarded after the contents of the bucket has been used.

15 Other objects and advantages of the invention will become apparent to the reader of the following specification.

In the drawings—

Figure 1 represents a top plan view of a paint bucket equipped with the attachment.

Figure 2 is a perspective view of the attachment.

Figure 3 is a sectional view taken substantially on a line 3—3 of Figure 1, showing the brush in broken lines supported by the hanger rod.

Figure 4 is a fragmentary detailed sectional view approximately on the same line of Figure 1 as on which Figure 3 is taken, but showing the brush in broken lines being used in conjunction 30 with the wiper bar, and showing the paddle in broken lines in supported position.

Figure 5 is a fragmentary detailed sectional view taken substantially on a line 5—5 of Figure 1.

35 Referring to the drawings wherein like numerals designate like parts, it can be seen that numeral 5 represents the usual bucket having a bail 6.

The attachment is generally referred to by numeral 7 and consists of the U-shaped brush hanger rod 8, one upstanding leg portion 9 of which is bent around one end portion of the arcuate wiper rod 10 as at 11. The other upstanding leg 12 of the hanger rod 8, which is only slightly curved in 45 comparison to the curvature of the wiper rod 10, is bent over the opposite end portion of the wiper rod 10 as at 13 and then disposed downwardly as at 14 and laterally as at 15. The lateral por-

tion 15 is then offset inwardly as at 16 and then has the extending arm portion 17 which serves as a paddle holder, for holding the paddle 18 against one side of the can, as suggested in Figure 4.

The end portions of the wiper rod 10 are bent 5 upwardly as at 19 and then outwardly and downwardly as at 20 from where the end portions are disposed inwardly as at 21 and laterally as at 22, thus forming spring portions 21—22 which will bear against the outside of the can tensionally 10 when the hook portions 19—20 are engaged over the rim of the can.

Thus it can be seen that the wiper rod 10 is supported by the hooks 19—20 at each end thereof, while in turn the hanger or supporting rod 8 is 15 suspended from the wiper rod 10.

The brush when not in use is supported by the rim of the can and the hanger rod 8 as adjusted in Figures 1 and 3. However, when the brush is 20 in use and some of the surplus paint is to be wiped off of the same, the brush is wiped along the rod 10 as suggested in Figure 4.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is—

A receptacle attachment of the character described comprising a rod having hooks at the ends thereof adapted to engage over the upper edge portion of a receptacle, and being offset in an upward direction to permit the rod to be located 35 below the upper edge of the receptacle, a U-shaped member having its end portions secured to the rod and adapted to define a rest member for the brush end of a paint brush, one end of the U-shaped member being provided with a lateral 40 extension disposed in substantially right angular relation with respect to the rod and U-shaped member adapted to extend in close proximity to an inside portion of a receptacle in which the attachment is located to define a paint mixing 45 paddle holder.

ROBERT A. SPITZ.
